UNITED STATES PATENT OFFICE.

VICTOR GERO, OF PHILADELPHIA, PENNSYLVANIA.

TUFT-YARN FRAME FOR LOOMS.

1,272,656.

Specification of Letters Patent.

Patented July 16, 1918.

Application filed May 14, 1918. Serial No. 234,519.

To all whom it may concern:

Be it known that I, VICTOR GERO, a subject of the King of Great Britain, and a resident of Philadelphia, in the county of 5 Philadelphia and State of Pennsylvania, have invented certain new and useful Improvements in Tuft-Yarn Frames for Looms, of which the following is a specification.

10 Some of the objects of the present invention are to provide a tuft yarn frame which is arranged to operate continuously for a long period without requiring repairs, replacement or adjustment; to provide a 15 means for permanently securing fastening clips to a tuft yarn frame; to prevent the spring clips of a tuft yarn frame from working loose during the operation of the frame; to provide means to prevent the spring clip 20 fastening devices of a tuft yarn frame from projecting into the path of other parts stationary or movable with respect to the frame; and to provide other improvements as will hereinafter appear.

25 In the accompanying drawings, Figure 1 represents a side elevation of a tuft yarn frame embodying one form of the present invention; Fig. 2 represents an enlarged end portion of the same part in section and part 30 in side elevation; Fig. 3 represents an end elevation of the same; and Fig. 4 represents a bottom plan of an end of the frame.

35 Referring to the drawings one form of the present invention is shown in operative position upon a tuft yarn frame of the usual type consisting of a relatively long narrow bar 10, preferably of wood, which forms a support for a plurality of yarn carriers 11. These carriers 11 are customarily of metal 40 in the form of hollow tubes located side by side and each serving to guide the yarn from the spool (not shown).

45 For the purpose of supporting and journaling the tuft yarn spool in operative relation to the carriers 11 suitably apertured ears 12 are respectively formed upon end members 13 carried by the respective ends of the frame 10. These members 13 each have a base part 14 arranged to seat against 50 a bottom portion of the frame 10 so that the general shape of the members 13 is that of a right angular piece, both parts of which lie in contact with the frame, giving a snug fit and being rigidly held by screws 15, or 55 like fastening devices which pass into frame 10. Thus in assembled position as shown in

Fig. 1, the end members 13 extend upwardly at each end of the frame and substantially perpendicularly thereto in order to bring the ears 12 into alignment above the frame 60 10 to correctly position the spool.

In order to detachably connect the frame 10 to the chain or part of the loom by which it is automatically picked up and operated, the members 13 each have a laterally projecting and upwardly bent finger 16 for engagement with the chain and adapted to be held in engagement by a spring clip 17. The spring clip 17 for each member 13, is secured at one end to its member 13 by a 65 screw, stud or pin 20 having a head 21 seated in a recess portion of the frame 10 and there held by the member 13, while the body portion of the screw is threaded through the member 13 to project sufficiently to receive 70 the clip 17 and a retaining guard 22, both of which are suitably apertured for the purpose. The guard 22 is an angular piece conforming to the contour of the angular part of the member 13 to which it is made fast 75 by one of the screws 15 and an additional screw 18 suitably spaced for the purpose intended. It should be noted that the screws 15 preferably intersect a wooden or soft metal plug 19 embedded in frame 10, so that 80 the screws are prevented from easily working loose as will be understood.

85 For the purpose of maintaining a suitable tension upon the spool when in operative position, a pair of spring arms 23 are fixed 90 to the frame 10 in the usual position and manner.

In assembling the clip 17 and its locking or clamping parts, the stud screw 20 is properly placed in position in the member 13 and 95 the latter then secured to the end of the bar 10 by the horizontally disposed screw 15, the head 21 of the screw seating in the recess of the portion of the bar as heretofore described. The spring clip 17 is then placed 100 over the projecting end of the screw or pin 20 in contact with the member 13 whereupon the retaining guard 22 is seated upon the bar 10 and the clip 17 and the remaining fastening devices 15 inserted into the frame 105 to simultaneously clamp the member 13, the spring clip 17 and the guard 22 together. It should be noted that the length of the fastening stud 21 is substantially 110 equal to the combined thickness of the member 13, spring 17 and guard 22 in order not to project beyond the guard and interfere

with adjacent parts. Furthermore the guard 22 merely acts as a retainer or end clamp to prevent displacement of the clip 17, while leaving the major part of the 5 length of the latter free for the necessary spring action.

In the tuft yarn frames as heretofore employed the securing means for the spring clip elements has been such as to cause infinite trouble due to the fact that the continued picking up of the frames by the 10 chains, as well as their movement, has caused the fastening device to work loose. The result of this is to render the clips ineffective 15 and a frequent source of trouble is the damaging of adjacent parts by the loose screws which back out and project so as to strike fixed or moving parts. In practice, mills have found it absolutely essential to employ 20 special repairers for the purpose of keeping the clips tight, replacing broken clips and repairing frames damaged by the displaced clip securing means.

By the present invention the foregoing 25 defects are entirely overcome and the clip holding parts become permanent attachments to the tuft frame and cannot work loose or project in such a manner as to interfere with other parts of the loom.

30 It will now be apparent that a novel and useful device has been devised, which embodies the features of advantage enumerated as desirable in the statement of the invention and the above description, and while in the 35 present instance the preferred embodiment is shown and described, it is to be understood that the same is susceptible of modification in various particulars without departing from the spirit or scope of the invention 40 or sacrificing any of its advantages.

What I claim is:

1. In a device of the character stated, a

tuft yarn frame, a member secured thereto, a spring clip, and means clamped between said frame and said member for supporting 45 said clip.

2. In a device of the character stated, a tuft yarn frame, a member secured thereto, a spring clip, a means carried by said member for supporting said clip, and a guard 50 fixed to said frame for preventing displacement of said clip.

3. In a device of the character stated, a tuft yarn frame, a member secured thereto, a spring clip, supporting means for said 55 clip fixed by said member and including a projecting part to receive said clip and a guard seating over the end of said means and fixed to said frame.

4. In a device of the character stated, a tuft yarn frame, a member secured thereto, a headed pin passing through said member and having its head clamped between said member and said frame, a spring clip seating on said pin and a guard fixed to said 65 frame to maintain said clip in operative position upon said pin.

5. In a device of the character stated, a tuft yarn frame, a member disposed at right angles to the back of said frame and secured 70 to the end of said frame, a pin projecting laterally outward from said member, a spring clip arranged to seat on said pin, and a guard fixed to said frame to maintain said clip in operative position upon said pin. 75

6. In a device of the character stated, a tuft yarn frame, members secured respectively to the ends of said frame, a laterally projecting pin for each member, spring clips respectively seating on said pin and a guard 80 for each end of said frame arranged to prevent displacement of said spring clips.

VICTOR GERO.
